ATTORNEY

UNITED STATES PATENT OFFICE.

TIMOTHY A. REMSEN, OF BROOKLYN, NEW YORK.

SWITCH FOR RAILROAD-CARS.

SPECIFICATION forming part of Letters Patent No. 508,837, dated November 14, 1893.

Application filed January 26, 1893. Serial No. 459,880½. (No model.)

To all whom it may concern:

Be it known that I, TIMOTHY A. REMSEN, a citizen of the United States, and a resident of Brooklyn, in the county of Kings and State 5 of New York, have invented certain new and useful Improvements in Switches for Electric-Railroad Cars, of which the following is a specification.

My invention is adapted to street cars and 10 more particularly to electric street cars and it consists in a novel construction, arrangement, and operation, of devices for switching a car from one track to another by means of the car wheels themselves, as hereinafter 15 more particularly described.

In the accompanying drawings Figure I is 20 a top view of a mechanism embodying my improvement. Fig. II is a side view thereof. Figs. III and III* are views showing face of 25 the wheel.

Similar letters of reference indicate corresponding parts.

The letter A indicates a rail road track 25 constructed with a switch tongue A' pivoted at a in the usual manner where a car is to be switched from one track to another, and the letter B represents a part of the body of the car which is supported upon wheels, the tread of the forward left or right hand wheel 30 being of the form as shown at C (Figs. III and III*) to be hereinafter more particularly described.

The letter D indicates a casing or frame 35 constructed of iron, wood or any other suitable material which is sunk in the ground as shown in dotted lines in Fig. I. Arranged in this casing D and to the inner sides of the track A are pivoted thereto, as at b, levers E E' which extend slightly above the level of 40 the tracks A and their forward ends C impinging against the lower portion of bell crank levers G G' pivoted to lugs e on the bottom of the casing D. The said levers E E' are provided on the lower rear portion with 45 weights to keep a part of their upper portion above the track. To the upper end of the bell crank lever G' is connected one end of the cross rod H which passes through an opening on the under side of one of the tracks A, 50 while to the other end of said rod H is connected the end of the switch tongue A' by inserting the rod therein. The bell crank lever G is attached to the rod H near the end thereof, so that when the lever E or E' is operated 55 upon it actuates the bell crank levers G and

G' which in turn move the switch tongue A' through the medium of the rod H.

In this example the letter C indicates a forward right hand car wheel having its face or tread constructed with a double or inner bearing f, as shown in Fig. III while the other wheels of the car are of the ordinary construction.

The operation is as follows: When the car 65 is moving in the direction shown by the arrow the flange f of the right hand wheel C will press the lever E' which in turn actuates the bell crank lever G' which causes the switch tongue A' to be shifted to the left and the car is switched to the right hand track, 70 while if it is desired to shift or switch the cars to the left hand track the tread f of the forward left hand wheel of the car would be constructed as shown at C Fig. III which would press on the lever E near the left hand track 75 and operate the switch tongue A' by means of the bell crank levers G and G' and rod H. If it is desired to switch the car a second time the tread of the wheel C may be constructed with an additional bearing f' for that purpose as shown in Fig. III*.

By my arrangement the switch may be set by one car one way and by another car the other, by means of interior treads of the wheels and without being actuated either 85 way by the carrying tread of either wheel, thereby dispensing with the services of a man at each switch and doing away with the old style switches operated by the horses' feet.

My invention is particularly adapted for 90 the use of electric street rail road cars that will operate the switches themselves instead of requiring the presence of a man at each switch, and moreover it can be used with equal advantage on horse cars as well. 95

What I claim as new, and desire to secure by Letters Patent, is—

In combination the rail A, the levers E, E' arranged in the casings alongside of the inner margins of the rails with a part projecting 100 above the rails and their forward ends impinging against the bell crank levers G, G', and the cross bar H connecting the bell crank levers G G' and the switch tongue, substantially as shown and described.

TIMOTHY A. REMSEN.
